UNITED STATES PATENT OFFICE.

RICHARD SIMON, OF SAN FRANCISCO, AND DE LOS C. BUTTS, OF OAKLAND, CALIFORNIA; SAID BUTTS ASSIGNOR TO SAID SIMON.

NOVELTY SAVINGS BANK.

Application filed June 1, 1926. Serial No. 112,802.

The invention relates to a toy bank operated in connection with an alarm clock.

An object of the invention is to provide a savings bank so associated with an alarm clock that the ringing of the alarm may only be stopped upon the deposit of a coin in the bank.

Another object of the invention is to provide means, operated by the clock, for restoring the operativeness of the alarm mechanism after it has been rendered inoperative by the deposit of the coin.

A further object of the invention is to provide a toy bank with the foregoing features, in which coins may, if desired, be deposited without affecting the alarm operation.

The invention possesses other objects and features of advantage, some of which, with the foregoing, will be set forth in the following description of the preferred form of our invention which is illustrated in the drawings accompanying and forming part of the specification. It is to be understood that we do not limit ourselves to the showing made by the said drawings and description, as we may adopt variations of the preferred form within the scope of our invention as set forth in the claims.

Referring to said drawings:

Figure 1 is a vertical section through a bank involving one embodiment of the invention.

Figures 2 and 3 are perspective views of the bank viewed from the front and rear respectively, a portion of the structure being broken away in Figure 3 to show the pivotal mounting of the back plate of the casing.

Figure 4 is a perspective view of a member forming part of the structure.

As illustrated in the embodiment of the invention shown in the drawings, the bank comprises a casing 4 which is arranged to contain the mechanism of the device and the coins deposited therein. Arranged within the casing and suitably supported therein is an alarm clock 6, the face of which, as here shown, is visible through the front wall of

the casing. The casing is provided with a hinged closure plate 8 which forms the rear wall of the receptacle and is pivoted in the casing side walls adjacent the bottom thereof to allow access to the interior of the casing when it is swung to an open position. The various winding and setting members at the back of the clock are arranged to project through the plate when the latter is in closed position, the plate being as here shown formed with an opening 9 to accommodate said members and thereby allow the unhindered swinging of the plate between the closed and open positions thereof.

The alarm clock 6 may be of the usual form, and as here shown, the alarm mechanism thereof includes a clapper 12 which is caused to vibrate and beat against a bell 13 at the time set for the alarm. Preferably, however, the usual means provided on the clock for rendering the alarm mechanism inoperative is dispensed with, or if not dispensed with is at least made inaccessible from the exterior of the bank, so that if the time and alarm mechanism are properly wound, the alarm at the time set will ring unrestrained until the alarm actuating means has completely run down. Means, however, are provided whereby a person may, by depositing a coin in the bank, interrupt the alarm during the ringing thereof. In the present embodiment of the invention, such interruption is effected by causing the clapper 12 to be held from continuing its vibrating movement as soon as the coin is inserted in the bank. Preferably located within the receptacle and defined between plates 16 and 17 is a coin passage 18, the entrance to which from the exterior of the casing is had through an opening 19. The plate 16 is stationary, whereas the plate 17 is hinged at its upper end for movement to and from the plate 16, and is provided with side and bottom flanges 21 in order that a coin, when dropped through the opening 19, will be retained in the passage 18 when plate 17 is held against the plate 16, a spring 22 serving

to normally hold the plate 17 in such position.

Fixed to the clapper 12 is an extension 23 which protrudes from the side of the clock 5 and is arranged to pass through an opening 24 of the plate 16 into the coin passage 18. Normally, when the clapper, in the course of actuation of the alarm, is caused to vibrate, the free end of the extension 23 reciprocates freely in the passage 18. Should, however, an obstruction be placed in the passage in the path of the extension, movement of the latter will be stopped and the ringing of the alarm thus halted. It will be noted 10 from Figure 1, that the form of the passage 18 is such that when a coin is dropped into the passage it will be retained therein in opposed relation to the opening 24 and thus in the direct path of movement of the clapper extension. In this manner, therefore, the simple deposit of the coin in the device 20 will cause the ringing of the alarm to immediately cease.

Means are provided for automatically releasing the coin from the passage and allowing it to pass into the depository or savings compartment of the bank, after the clock hands have moved beyond the time set for the ringing of the alarm, since the alarm will 25 not then ring again until the hands have again moved to the time set for the ringing of the alarm. Furthermore by thus releasing the coin, the alarm mechanism will be ready to ring in accordance with the next 30 setting. Secured to the plate 17 to extend forwardly from the edge of the bottom flange thereof through a properly positioned slot in plate 16 and into the clock mechanism is an arm 27 whose free end 28 is arranged to lie in the path of a projection 29 fixed to a gear 31 suitably driven by one of the gears of the clock mechanism. It will 35 now be clear that when the projection trips the arm the plate 17 will be swung backward and the coin will be discharged from the passage, thus permitting the unhampered movement of the clapper extension 23.

Should it be desired to deposit a coin in the bank without interfering with the alarm 40 mechanism, the plate 17 may be withdrawn by means of a knob 32 which is secured to a rod 33 protruding from the back of the plate 17 to extend through a perforation provided in the casing whereby it is accessible from 45 the exterior of the device. As here shown, the rod 33 is arranged to provide a mounting for the spring 22, which spring is of helical form whereby the rod may be disposed therethrough and the spring may be operatively 50 engaged between the plate and casing.

We claim:

1. In a coin depository, a clock associated therewith and provided with alarm means and a mechanically controlled actuating 55 mechanism therefor, a coin passage to said

depository arranged to have a coin trapped therein for rendering said mechanism inoperative, and means to release said coin whereby said alarm means may be restored to operative condition.

70

2. In a coin depository, a clock associated therewith and providing an alarm mechanism including a clapper, a coin conduit to said depository including a coin trapping member arranged to receive and hold said coin in a position to mechanically render said clapper inoperative, and means operated by the clock mechanism for automatically releasing the coin entrapped by said member and thereby restoring the alarm 75 mechanism to operative position.

3. In a novelty savings bank, a receptacle arranged to be locked shut, a clock mounted therein with the winding members thereof arranged for access from without the receptacle and provided with an alarm bell and a clapper therefor, and means operative upon the insertion of a coin in the bank for engaging said clapper to prevent the actuation 80 thereof.

85

4. In a novelty savings bank, a housing having a coin depository therein, a clock in said housing having an alarm bell and a clapper therefor, a coin passage in said housing communicating with said depository and including coin trapping means arranged to so engage said clapper as to render the alarm mechanism inoperative when a coin is entrapped thereby, manually operative means to render said trapping means inoperative, 100 and independent automatic means for rendering said trapping means inoperative.

5. A novelty bank comprising a housing having a coin depository therein, a clock in said housing having the winding members 105 arranged for access from the exterior of the housing and having an alarm mechanism including a clapper lying within the housing, a coin conduit in said housing leading to said depository from the exterior of the 110 housing and including coin trapping means, means extending from said clapper to within said conduit for engagement with an entrapped coin whereby movement of said clapper will be prevented when a coin is entrapped in the conduit, and means operative by the clock mechanism for releasing the entrapped coin after the time set for ringing the alarm has passed.

115

6. In a coin depository, a clock associated therewith and provided with an alarm mechanism automatically operated control means, and means by which a coin may be passed into said depository to render the alarm 120 mechanism inoperative.

125

7. In a coin depository, a clock associated therewith and provided with alarm means having a solely mechanically controlled actuating mechanism therefor, a coin passage to said depository, and means operative 130

upon the deposit of a coin in said passage for rendering said alarm mechanism inoperative.

8. In a coin depository, a clock associated with the depository and provided with alarm means and mechanically controlled actuating mechanism therefor, means arranged to receive a coin for said depository whereby said mechanism may be rendered inoperative,

and automatic means for permitting the coin ¹⁰ to drop into the depository thereby releasing the alarm mechanism.

In testimony whereof, we have hereunto set our hands at Oakland, California, this 3rd day of May, 1926.

RICHARD SIMON.
DE LOS C. BUTTS.
